UNITED STATES PATENT OFFICE.

THOMAS AUGUSTUS LITTLEJOHN, OF PAINESVILLE, OHIO.

SHOE-STRETCHER.

1,100,752.

Specification of Letters Patent. Patented June 23, 1914.

Application filed September 11, 1913. Serial No. 789,241.

To all whom it may concern:

Be it known that I, THOMAS AUGUSTUS LITTLEJOHN, a citizen of the United States, residing at Painesville, in the county of 5 Lake and State of Ohio, have invented certain new and useful Improvements in Shoe-Stretchers, of which the following is a specification.

My invention relates to devices for 10 stretching shoes lengthwise and laterally.

In the construction of the shoe stretcher at present in common use, the body portion or form is in two halves, being divided longitudinally. The lateral stretching is accomplished by a rod threaded into a sleeve 15 mounted on trunnions in the heel portions of the form, the forward end of said rod being swiveled to a wedge, adapted to spread the forward parts of the form when the rod is screwed forward. There being no longitudinal 20 adjustment of the form, there is no buttress for the rear thrust of the operating rod, consequently unless the form fits snug endwise in the shoe, as the wedge is forced forward. 25 The whole form slides rearward. Thus the utility of the device is limited, as it is not possible to accommodate the same stretcher to various lengths of shoes and maintain the pressure at the desired point 30 without interposing blocks or other suitable packing in the heel as a buttress for the longitudinal thrust. The stretching functions of the ordinary device are also confined to the lateral movement, there being no provision 35 for a longitudinal stress.

The objects of my invention are the provision of means whereby the shoe may be stretched lengthwise or laterally with the same device, and whereby the pressure necessary 40 for the lateral stretching is readily applied at the desired location, and when sufficient stress has been applied, the operative parts of the device are held in a positive position, thereby maintaining the pressure at 45 the exact part of the shoe it is desired.

Another object of the invention is to provide 50 a device for the purpose set forth, wherein stretching forms of different contour, adaptable to different shapes of shoes, may be readily substituted and applied to the same operating mechanism.

With these objects in view the invention consists in the construction, combination and arrangement of the parts described in the

specification, illustrated in the drawings and 55 pointed out definitely in the claims.

In the drawings Figure 1 is an elevation of the improved stretcher. Fig. 2 is a plan view in the direction of arrow *a*, Fig. 1, showing a portion of the forms in section. 60 Fig. 3 is a longitudinal section. Fig. 4 is a section through the cam housing, on line 4-4, Fig. 2, and Fig. 5 is an end view of the cam housing detached, and a cross-section of the worm shaft. 65

Similar characters of reference are used to designate similar parts in the drawings and specification.

Referring now to the drawings 1, 1 are the stretching members or forms, these may 70 be of various different contours externally, making them adaptable to different styles of shoes. The forms 1, 1 are pivotally attached to a bracket 2 by the hinge member 1^a, the butts 2^a, and the pintles 2^b, forming hinges 75 which admit of a lateral movement of the forms.

A buttress 3, adapted to rest in the rear end of the shoe and bear on the counter, forms a housing in which an internally 80 threaded sleeve 4 is mounted on lateral trunnions 4^a, 4^b. A tubular member 5 is threaded in the sleeve 4, and extends through an opening 2^b in the bracket 2. An annular shoulder 5^a bears on one side of said bracket, and a 85 retaining nut 5^b bears on the other side, sufficient clearance being allowed to permit the member 5 to turn freely in the opening 2^b.

The meeting faces of the forms 1, 1 are provided with recesses 1^b, adapted to incase 90 a member 6, which forms a housing for the cams 7, 7 which are mounted on the axles 7^a, 7^b.

A rod 8 extends longitudinally through the tubular member 5, and has a terminal 95 bearing 8^a in the member 6. The rod 8 is provided with a worm 8^b, which meshes with worm segments 7^b, 7^b on the cam members 7, 7. The rod 8 is also provided with an annular shoulder 8^c which has a thrust bearing 100 on the end of the member 5 or on the retaining nut 5^b.

The outer terminal of the member 5 is provided with a hand-wheel 5^c, or other suitable means for operation, and the rod 8 105 is provided with similar means 8^d, being so arranged as to admit of the independent operation of the two members 5 and 8.

It will readily be seen, that when the device is inserted in a shoe, with the member 3 seated in the rear thereof, bearing on the counter, and the member 5 is propelled in 5 the direction of arrow *b*, Fig. 1, the bracket 2 is forced forward, and carries the forms 1, 1 with it. It also carries the member 6 and its attachments with it, through the medium of the shoulder 8.

10 The elongating or longitudinal stretching of the shoe is accomplished by the coöperation of the members 3, 4, and 5 and the bracket 2 and forms 1, 1. The lateral stretching is accomplished by forcing the 15 forms forward to the desired point, and then turning the rod 8 to the right. The worm 8^b being in mesh with the worm segments 7^b, 7^b, causes the cams 7, 7, bearing on the walls 1^c of the recesses 1^b, to spread the 20 forms more or less as desired. The longitudinal position of the forms is maintained during the application of the lateral stress by the counter of the shoe receiving the thrust.

25 I have herein described and shown a simple embodiment of the invention, but I do not consider that I am confined to this particular detailed construction only so far as limited by the claims and the existing state 30 of the art.

Having now described my invention, what I claim and desire to secure by Letters Patent is—

1. In a shoe stretcher, the combination of 35 a buttress member to be placed in the rear of the shoe; stretcher members to be placed in the forward part of the shoe; a member interposed between the buttress and the stretcher members; a hinged connection be- 40 tween the stretcher members and the inter- posed member; a tubular member having a threaded connection with the buttress mem- 45 ber and a bearing on the interposed member; mechanism in the stretcher members for imparting lateral movement to said mem- bers; and actuating means for said mecha-

nism extending through the tubular member and operative independent of said tubular member.

2. In a shoe stretcher, the combination of 50 a buttress member adapted to be placed in the rear of the shoe and bear on the counter; a tubular member having a longitudinal threaded connection with the buttress; a bracket having a swivel connection with the 55 forward end of the tubular member; stretcher forms pivotally connected with said bracket; mechanism interposed between the stretcher forms for imparting lateral movement to said forms; and actuating 60 means for said mechanism extending through the tubular member and adapted to be operated independent of said tubular member.

3. In a shoe stretcher, the combination of 65 a buttress member; an internally threaded sleeve mounted in said buttress member; a tubular member threaded through said sleeve; a bracket swiveled to one end of 70 said tubular member; stretcher forms pro- 75 vided with recesses, connected with said bracket and adapted to be moved toward and away from each other; mechanism in said recesses for moving the forms; and actuating means for said mechanism ex- tending through the tubular member.

4. In a shoe stretcher, the combination of 80 a buttress member; an internally threaded sleeve mounted on trunnions in said buttress; a tubular member threaded through said sleeve; a bracket swiveled to one end of 85 said tubular member; stretcher forms provided with recesses and having a laterally movable connection with the bracket; a housing mem- ber within said recesses; cams mounted in 90 said housing; and means for operating said cams, whereby a lateral movement is im- parted to the forms.

THOMAS AUGUSTUS LITTLEJOHN.
